(57) **CLAIM**

The ornamental design for a label printer, as shown and described.

DESCRIPTION

FIG. 1 is a front, top, and left side perspective view of a label printer showing our new design;

FIG. 2 is a rear, bottom, and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines are for illustration only and form no part of the claimed design.

1 Claim, 8 Drawing Sheets

FIG. 1

FIG. 2***FIG. 3***

FIG. 4***FIG. 5******FIG. 6****FIG. 7*
